UNITED STATES PATENT OFFICE.

HARLEY T. PECK, OF LEBANON, OHIO, ASSIGNOR TO THE PETERS CARTRIDGE COMPANY, OF CINCINNATI, OHIO, A CORPORATION OF OHIO.

PRIMER FOR SMALL-ARMS AMMUNITION.

1,416,122.

Specification of Letters Patent. Patented May 16, 1922.

No Drawing.

Application filed July 20, 1921. Serial No. 486,224.

To all whom it may concern:

Be it known that I, HARLEY T. PECK, a citizen of the United States, residing at Lebanon, in the county of Warren and State of Ohio, have invented certain new and useful Improvements in Primers for Small-Arms Ammunition, of which the following is a specification.

This invention relates to a priming composition for ammunition and has for its object the provision of a substance of the class named which shall be of improved composition and efficiency.

The invention is exemplified in the composition of material described in the following specification, and it is more particularly pointed out in the appended claims.

A priming composition made according to the present invention has pronounced qualities of sensitiveness, freedom from fouling in the barrel of the fire-arm, improved qualities of ignition with propellants, and increased uniformity of all ballistic qualities. It will function in a more uniform manner than priming compositions heretofore known and is more independent of variations which may exist within the primer or cartridge in which it is used.

In a center-fire or rim-fire primer made according to one embodiment of my invention, the combination of substances used to produce a primer of improved sensitiveness contains a sulpho-cyanate, di-plumbic di-tri-nitro-resorcinol, tri-nitro-resorcinol and an oxidizing agent. When these substances are mixed together there is a slight but complicated chemical reaction which I consider to be responsible for the improved properties described above.

40 The following proportions are given by way of example of a priming composition containing these substances:

5% by weight of tri-nitro-resorcinol.

5% by weight of lead sulphocyanate.

45 40% by weight of di-plumbic di-tri-nitro-resorcinol.

50% by weight of potassium chlorate.

The chemical formula for di-plumbic di-tri-nitro-resorcinol is $Pb_2O_4Cl_2H_2(NO_2)_6$, 50 the use of which in a priming composition is described in my Patent No. 1,350,465, granted August 24th, 1920.

The proportions of the materials may be varied to meet different requirements. For some purposes the following proportions 55 may be used:

15% by weight of tri-nitro-resorcinol.

20% by weight of lead sulphocyanate.

15% by weight of di-plumbic di-tri-nitro-resorcinol. 60

50% by weight of potassium chlorate.

Rim-fire cartridges in general require a somewhat different type of composition from center-fire, and for such cartridges an abrasive substance, such as ground glass, emery 65 or ferro-silicon, may be added to the composition. A suitable composition for rim-fire cartridges may contain—

30% di-plumbic di-tri-nitro-resorcinol.

10% lead sulpho-cyanate. 70

10% tri-nitro-resorcinol.

20% potassium chlorate.

30% ground glass.

In place of lead sulpho-cyanate, some other suitable cyanate such as copper sulpho-cyanate may be substituted. 75

Instead of potassium chlorate another oxidizing agent such as potassium perchlorate, barium nitrate, barium peroxide or other oxidizing substances, may be used. 80

Instead of di-plumbic di-tri-nitro-resorcinol other suitable detonating explosives, such as mercury fulminate, normal lead tri-nitro-resorcinol, one of the organic diazo compounds, or some detonating nitro compound, 85 such as tri-nitro toluene, tri-nitro nitro-anilid or tri-nitro methyl nitro-anilid may be used.

The priming compositions of the present invention may be mixed and introduced into 90 the primer cup or rim-fire shell in the usual manners well known to those skilled in the art.

I claim:—

1. A priming composition containing tri-nitro-resorcinol, a sulpho-cyanate, an oxidizing agent and di-plumbic di-tri-nitro-resorcinol. 91

2. A priming composition containing tri-nitro-resorcinol, lead sulpho-cyanate, an oxidizing agent and di-plumbic di-tri-nitro-resorcinol. 1

3. A priming composition containing tri-nitro-resorcinol, a sulpho-cyanate, potassium

chlorate and di-plumbic di-tri-nitro-resorcinol.

4. A priming composition containing tri-nitro-resorcinol, lead sulpho-cyanate, potassium chlorate, di-plumbic di-tri-nitro-resorcinol and an abrasive substance.

In testimony whereof I have signed my name to this specification on this fifth day of July, A. D. 1921.

10

HARLEY T. PECK.

5. A priming composition containing tri-
